Primary Examiner—Philip S. Hyder*Assistant Examiner*—Adir Aronovich*Attorney, Agent, or Firm*—Michaelson & Wallace[57] **CLAIM**

The ornamental design for a adjustable violin and viola chinrest, as shown and described.

DESCRIPTION

FIG. 1 is a front perspective view of the claimed invention;

FIG. 2 is a back view of the claimed invention;

FIG. 3 is a top view of the claimed invention;

FIG. 4 is a bottom view of the claimed invention;

FIG. 5 is a first side view of the claimed invention;

FIG. 6 is a second side view of the claimed invention; and,

FIG. 7 is a front view of the claimed invention.

The broken lines shown in FIGS. 2-7 are for illustrative purposes only and form no part of the claimed invention.
